BAROMETER TEST CHAMBER

James Robert King, Van Nuys, and Gerald D. Myers, Sepulveda, Calif., assignors to King Nutronics Corporation, Van Nuys, Calif.

Filed May 5, 1972, Ser. No. 250,863

Term of patent 14 years

Int. Cl. D10—05
U.S. Cl. D16—2 C

FIG. 1.

FIG. 2.

FIG. 3.

FIG. 1 is a perspective view of a barometer test chamber showing our new and novel design;

FIG. 2 is a top plan view of the barometer test chamber of FIG. 1; and

FIG. 3 is a side view thereof.

I claim:

The ornamental design for a barometer test chamber, substantially as shown.
